UNITED STATES PATENT OFFICE.

THEODORE P. CASE, OF POWELL, OHIO.

VEHICLE-TONGUE.

SPECIFICATION forming part of Letters Patent No. 278,505, dated May 29, 1883.

Application filed January 11, 1883. (No model.)

To all whom it may concern:

Be it known that I, THEODORE PHILO CASE, of Powell, in the county of Delaware and State of Ohio, have invented a new and useful Improvement in Vehicle-Tongues, of which the following is a full, clear, and exact description, reference being had to the annexed drawings, forming part of this specification.

The object of this invention is to provide an adjustable tongue for mud-sleds and other vehicles, which may be secured in a rigid position, or adapted to oscillate to either side, as and for the purpose hereinafter described.

In the drawings, Figure 1 is a plan view of the tongue and a part of the sled, and Fig. 2 is a longitudinal section of the tongue.

Sleds frequently become tightly frozen to the ground in winter, and to loosen them conveniently requires that the tongue shall be adapted to turn to one side, so that a partially lateral draft may be brought to bear upon the runners to wrench them out of the frozen earth or ice. If the tongue, however, is flexibly connected to the sled, without means for rendering it rigid at will, the loaded sled cannot be controlled when going downhill or along a slope. It therefore becomes necessary to provide means for rendering the tongue of the sled rigid or flexible at will. Accordingly I provide the tongue A with a plate, B, which is secured to the under side thereof, and adapted to project slightly beyond the same at the sides, and the front cross-bar, C, of the sled I provide with an oscillatory plate, D, having cleats E, which are adapted to overlap and hold the edges of the plate B. A sliding joint is thus formed between the tongue and said cross-bar, and the farthest backward movement of the tongue is limited by a downward-extending flange, F, at the forward end of the plate B, while the forward movement of the tongue is limited by the guy-chains G, which are connected to the tongue at H, and are secured to the cross-bar C by the eyebolts and nuts I J. The tongue is thus adapted to have an oscillatory movement to either side, while the guy-chains will equalize the draft when the tongue is drawn in a direct line.

As a means of rendering the tongue rigid at will, a stirrup, K, inclosing the upper surface of the tongue, is pivoted in ears L L, formed on opposite sides of the plate D, and the rear end of the tongue is provided with a

recess, M, into which the stirrup is adapted to drop when the tongue is drawn forward to its farthest limit. To lift the stirrup out of engagement with the recess M, a rod, N, which is pivoted in a groove, O, in the upper surface of the tongue, and has a crank, P, arranged in a recess, Q, in the rear end of the tongue, is to be turned by means of a handle or foot-piece, R, so that the said crank will lift the stirrup and allow the tongue to be oscillated with the oscillatory plate D. The tongue is to be provided with friction-plates wherever needed, to prevent wear from the contact of the stirrup. By thus attaching the tongue to the cross-bar C the double-trees are supported in a higher position than usual, which has the advantage of preventing them from striking the runners when the tongue is turned to one side.

The special features of my invention are capable of various modifications without departing from the general idea; and I therefore do not restrict my claim to the exact details of construction herein set forth.

What I claim as new, and desire to secure by Letters Patent is—

1. A sled or vehicle tongue which is adapted to form both an oscillatory and a longitudinally sliding joint with a stationary bar, combined with means for limiting the sliding movement, and for securing it in a rigid position at will, substantially as shown and described. 80

2. A sled or vehicle tongue which is adapted to form both an oscillatory and a longitudinally sliding joint with the cross-bar of the sled, combined with guy-chains for connecting it to the said cross-bar, and a stirrup for holding it in a rigid position at will, substantially as shown and described. 85

3. The combination of the tongue, the cross-bar, the flanged plate secured to the tongue, the oscillatory plate secured to the cross-bar, 95 the stirrup pivoted to the latter plate, the crank-rod pivoted in a groove in the tongue and adapted to lift the stirrup, and the guy-chains connecting the tongue to the cross-bar, all constructed and adapted to operate substantially as and for the purpose specified. 100

THEODORE PHILO CASE.
